MATTHEW M. MERRITT, OF MIDDLETON, MASSACHUSETTS, ASSIGNOR TO NATIONAL ELECTRIC LAMP COMPANY, OF CLEVELAND, OHIO, A CORPORATION OF NEW JERSEY.

INCANDESCENT LAMP.

No. 909,812.

Specification of Letters Patent.

Patented Jan. 12, 1909.

Application filed February 24, 1906. Serial No. 302,670.

To all whom it may concern:

Be it known that I, MATTHEW M. MERRITT, a citizen of the United States, residing at Middleton, county of Essex, and State of Massachusetts, have invented an Improvement in Incandescent Lamps, of which the following description, in connection with the accompanying drawings, is a specification, like letters on the drawings representing like parts.

My invention relates to improvements in incandescent lamps and has for one object the provision of a lamp so constructed as to prevent or render commercially impractical its renewal, or, in other words, the substitution, or attempted substitution of a new filament for the old one when the latter is burned out or otherwise rendered useless or inefficient.

It is a common practice to purchase at a relatively slight cost high grade lamps thus burned out, open the end or tip of the lamp and replace the old filament with a fresh one. The new filament having been attached to the leading-in wires, the lamp is exhausted by the usual process, the bulb sealed up, and the renewed or converted lamp in condition again for use. This renewing process is frequently conducted by irresponsible persons lacking the necessary skill and knowledge in the art and employing inferior materials, so that its product, in any event an inferior one, is very often a low grade lamp, though having every appearance of a high grade one. My invention aims to correct this practice, preventing possible injury to the reputation of the maker of the original lamp and deception of the public as well.

In the described embodiment of my invention this is accomplished by originally so constructing the lamp as to render difficult or impossible some one or more of the usual steps of the renewed process.

Another object of my invention, apart from and independent of its utility as a prevention of the renewal process, is the construction of an incandescent lamp having an improved connection between the filament and the leading-in wires.

My invention will be best understood by reference to the following description when taken in connection with the accompanying illustration of one specific embodiment there-

of, while its scope will be more particularly pointed out in the appended claims.

In the drawings,—Figure 1 shows a lamp embodying one form of my invention, and Fig. 2 shows on an enlarged scale and partially in section a detail showing the filament attachment in the lamp illustrated in Fig. 1.

Referring to the drawings and to the embodiment of my invention which I have there selected for illustration, there is shown a common form of incandescent lamp provided with the usual glass bulb *a*, cemented or otherwise secured in the usual fashion to and within the metal socket *b* and having the usual form of glass stem *c*, through which pass the leading-in wires *d* terminating in the sealed-in platinum ends *e*, the latter connected to the filament *f*.

In the ordinary lamp the platinum ends of the leading-in wires have each a free or interior portion projecting beyond the stem, which is ordinarily equal to or greater in length than the remaining sealed-in portion of the wire. When the filament is initially installed, the filament is placed with its ends in overlapping relation to these projecting leading-in wire ends and cemented thereto by joints of graphite paste. When renewal of the lamp is attempted, the tip of the lamp bulb having been perforated for this purpose, the old filament is removed, the platinum ends scraped clean of the old paste and a new filament attached thereto in the same fashion and by the same mode of attachment as originally.

In the described embodiment of my invention I have substituted for the binder or paste a metallic connection for the filament and platinum ends, the same herein comprising a small sleeve *g*, preferably of copper or other suitable material and of a size adapted approximately to fit over the platinum end of the leading-in wire. While this sleeve, if desired, could be first attached to the leading-in wire and the filament end thereafter secured within the same, preferably I first attach one to each end of the filament and secure them to the leading-in wire ends when the filament is installed. The sleeves being constructed of suitable diameter they may be merely slipped over the filament ends and secured thereto with any suit-

able tool which acts to crinkle, crimp or otherwise compress or distort the sleeve upon the filament end. If it is desired to attach the sleeve to the filament to secure good electrical contact therewith, without mechanical distortion, such result may readily be effected by maintaining the sleeve and its loosely contained filament end in an atmosphere of decomposed hydro-carbon gas and causing the latter to penetrate and deposit upon the interstices between the sleeve and the filament and secure the latter firmly within the sleeve. This process may be carried on simply by passing an incandescent current through the filament and sleeve while they are sustained in an atmosphere of hydro-carbon gas.

The filament with its sleeve attached as described may be installed by merely slipping the sleeve over the ends of the leading-in wires and by aid of a suitable tool compressing or crinkling the lower end of the sleeve, as indicated in Fig. 2.

It will be observed that the sleeve, however delicately it be constructed, will have a uniting strength greatly in excess of the ordinary graphite paste and that contact or union with the leading-in wires is required for a relatively short distance. Moreover, this mode of attachment permits the ends of the filament and leading-in wires to lie in abutment or opposition and does not require overlapping as does the pasted joint. The interiorly projecting or free portions of the platinum leading-in wire ends, therefore, may be, and preferably are, of considerably less length than in the ordinary lamp and shorter than the sealed-in portions thereof. For example, it is feasible to reduce the free platinum end to one-half or even one-quarter of its present length, leaving a projection of, say, one-sixteenth of an inch, or less, instead of approximately one-quarter of an inch as heretofore, thereby saving twenty-five per cent. or more on the total amount of platinum required for the leading-in wire ends, which, as is well-known, represents one of the most expensive features of the incandescent lamp.

The absence of paste or other porous matter in the joint is a marked advantage, for the absorption by the pasted joint of moisture and gaseous matter, which must be excluded during the exhaustion process, constitutes one of the principal difficulties in exhaustion. The pasteless joint, therefore, permits simplification and shortening of the exhaustion process.

The illustrated form of joint is not only simpler and more efficient than the paste, but permits more rapid installation of the filament and affords a standard or certain mounting for the latter. When the filament is pasted to the leading-in wires the effective length of the filament is dependent

in a measure upon the amount which its ends are caused to overlap the leading-in wires and this, particularly with negligent or careless operators, varies through a considerable range. This obviously causes corresponding variations in the resistance, candle power, voltage, and even the life of the filament. The use of the illustrated joint gives certainty as to the filament length and assurance that any number of filaments, when cut to the prescribed length, will each have its intended effective length when installed in its respective lamp.

In the described embodiment of my invention the renewal of the lamp by substituting a fresh filament for the old one through the use of graphite or other paste is practically impossible, for the free ends of the filament wires may be made so short as to render it impossible to unite a fresh filament thereto by the pasting process. If desired, the lamp may be constructed so as to commercially prevent the installation of a fresh filament by any means whatsoever. For example, in Fig. 2 I have shown the free platinum end of the leading-in wire *e* materially weakened, as at *h*, which can be done at the time of the original lamp construction by an appropriate tool, so that while having all needed and useful strength for supporting the filament, the strength of the leading-in wire at *e* is less than that of its attachment to the sleeve. Any attempt, therefore to withdraw or remove the sleeve connection from the leading-in wire will result in breaking off the latter close to the stem.

It will be evident that my invention as a means for preventing the renewal of the lamp need in fact be applied to but one of the two leading-in wires. That is to say, it is effective for this purpose if one leading-in wire end only is shortened or weakened as described, or the sleeve connection employed at one joint only.

A sleeve, or other like connection, may, if desired, be employed in connection with paste or other cement without the disadvantages usually accompanying the use of the latter. For example, the sleeve alone may first be applied to the end of the leading-in wire and clasped thereon. A small amount of paste having been placed in the open end of the sleeve, the filament end may be easily and quickly inserted, the hardening of the paste firmly uniting the filament to the sleeve. The amount of paste required is so small as to make a substantially non-porous and pasteless joint, while the operation of installing a filament is easier than the usual process where an all pasted joint is employed.

While I have described and shown one form of my invention in detail for the sake of illustration, it is to be understood that the same is not limited to the details thereof.

shown and described, but that extensive modifications and departures may be made therein without deviating from its spirit.

Claim—

- 5 1. An incandescent lamp having a bulb, a stem, a filament, and leading-in wires, one of said leading-in wires being relatively weak near the stem.
- 10 2. A non-renewable incandescent lamp having means forming a portion of the electric circuit of the lamp for injuring the lamp on the attempted withdrawal of the old filament.
- 15 3. A non-renewable incandescent lamp having means forming a portion of the electric circuit of the lamp for injuring the lamp on the attempted substitution of a new filament for the old one.
- 20 4. A non-renewable incandescent lamp having means for injuring a leading-in wire on attempted renewal of the lamp.
- 25 5. A non-renewable incandescent lamp having means operating to cause breakage

of a leading-in wire on attempted renewal of the lamp.

25

6. A non-renewable incandescent lamp having means for injuring the leading-in wires on attempted installation of a new filament.

7. An incandescent lamp having the leading-in wire *c* provided with the weakened portion *h*, the filament *f* and sleeve *g*.

8. An incandescent lamp having a filament, a weakened leading-in wire, and a metallic sleeve connecting the ends of the 35 filament and leading-in wire, said sleeve being compressed about one or both of the elements which it surrounds.

In testimony whereof I have signed my name to this specification in the presence of 40 two subscribing witnesses.

MATTHEW M. MERRITT.
